CHECKING INDICATOR FOR RAILWAY CARS

Filed March 30, 1928

Fig. 1.

Fig. 2.

UNITED STATES PATENT OFFICE.

CHARLES F. SCHELL, OF BUFFALO, NEW YORK, ASSIGNOR OF ONE-THIRD TO GEORGE SCHELL AND ONE-THIRD TO ROBERT W. SCHELL, BOTH OF BUFFALO, NEW YORK.

CHECKING INDICATOR FOR RAILWAY CARS.

Application filed March 30, 1928. Serial No. 265,875.

To check the destinations of various car passengers, conductors in taking up the tickets commonly use differently-colored paper slips or markers which, after punching, 5 they thrust under the hat-bands of passengers or into crevices of the upholstered seat-backs.

These slips or checks, being printed with day, month and year columns and used but 10 once, are a considerable item of expense and the punching operation requires more or less time.

The primary object of my invention is the provision of an inexpensive checking indicator which may be attached to the car-wall adjacent to each seat, so that as the conductor collects the tickets, he may by a simple and quick manipulation adjust the indicators at the various seats in accordance 20 with the stations or destinations called for by the tickets, thus indicating to him at a glance how far each passenger may travel and saving the cost of the paper checks and the time incident to their use.

25 A further object of the invention is the production of an indicator of this character which cannot be easily tampered with by passengers and which is neat and compact and at the same time affords an extensive bearing for the rotary parts of the device.

In the accompanying drawings:—

Figure 1 is a face view of the indicator secured to the wall of a railway car. Figure 2 is an enlarged transverse vertical section thereof on line 2—2, Figure 1. Figure 3 is a rear view of the same, partly in section. Figure 4 is a fragmentary vertical section similar to Figure 2 showing a modified construction of some of the parts. Figure 5 is a perspective view of the dial-wheel of said modification.

Similar characters of reference indicate corresponding parts throughout the several views.

45 The indicator shown in the drawing is of duplex construction to adapt it to two passengers occupying the same seat, one for the person sitting next to the wall of the car and the other for the one next to the aisle, 50 but the device may obviously be made with a single indicating member.

The indicator of each seat may be secured to the car wall between the adjacent windows, as shown. In the preferred form, its 55 casing has a front wall 10 provided with a

rearwardly extending rim 11, its back consisting of a base-board 12 which may be fastened to it by screws 13, the board in turn being screwed to the car-wall.

The two dial units are identical in construction. A description of one will therefore suffice for both. 14 indicates a rotary dial or dial-ring which has on its face a circular row of numerals 15 or other characters each of which indicates one of the stations along the railway line and which are exposed one at a time through a sight-aperture 16 in the front wall of the casing. Below this aperture is a collar or bearing 17 extending rearwardly from said wall and journaled in the bearing is a rotary cylinder 18 to which the dial 14 is connected to turn therewith. The bearing 17 may be integrally formed with the front wall of the casing 10 or it may be made separate, as shown 75 in Figure 2, and soldered or otherwise secured to the casing. In the embodiment of the invention illustrated in Figures 1, 2 and 3, the dial is provided with a rearwardly-extending annular rim or collar 19 having 80 an inwardly-extending annular web or member 20 which is soldered or otherwise fastened to the inner end of the cylinder 18. This construction results in a dial-wheel having a cupped central portion which receives 85 the bearing 17 and permits the dial itself to be brought closely to the sight-aperture 16 where its numbers can be easily read. This cupped form permits the use of a comparatively long bearing for the dial-journal 90 or cylinder, obtaining a durable construction and a reliable action of the indicator without increasing its bulk.

The cylinder is held against longitudinal displacement by suitable means, such as pins 95 21 projecting from the bearing 17 into an annular groove 22 of the cylinder. The latter has a longitudinal slot or key hole 23 adapted to receive a key 24 for turning the cylinder and the dial. This slot terminates 100 short of the cylinder bottom, which is provided with a small round hole 25, is adapted to receive an unlocking pin 26 at the front end of the key.

The dial is retained in any of its various 105 adjustments by a locking member, preferably consisting of a flat spring or blade 27 secured to a cleat 28 of the casing and provided at its free end with a stud 29 adapted to interlock with any one of a circular series 110

of openings or recesses 30 in the web 20 located in radial alinement with the respective numerals of the dial. The spring of this lock or catch normally bears against the back of the dial-wheel and extends over the opening 25 of the cylinder, so that upon inserting the proper key in the cylinder slot, the spring can be pushed to disengage its stud from the dial-wheel, as shown in connection with the spring of the upper indicator-unit in Figure 2, thus unlocking the dial and permitting its free rotation by the key whose body is flat-sided for this purpose.

To simplify the construction of the device and reduce its cost, the springs of the two units are formed of a single strip secured centrally to the cleat 28, as shown in Figures 2 and 3.

In the use of the invention, the conductor as he takes up a passenger's ticket, inserts his key in the hole of the corresponding indicator to unlock the dial after which he turns it until the number thereof which denotes the passenger's destination appears opposite the sight-aperture, when he withdraws the key to release the spring catch and again lock the dial. In this way, he sets the indicators of all the passengers and in passing through the cars after each train-stop he can tell by a glance at the indicators which of passengers boarded the train at the last station. Each dial remains locked until the corresponding passenger leaves the train and another takes his seat when the conductor resets the indicator accordingly.

As shown, the key holes of the double indicator may be distinguished by the letters "A" and "W", denoting the aisle and window seats, respectively.

The conductor's key and the key holes of the cylinders may be made of an irregular or unusual shape not easily duplicated, so that when an indicator is once set by the conductor for a passenger's destination, it remains so until changed by him for another passenger.

To baffle attempts to push the springs 27 out of engagement with the dial-wheels by a small wire nail or similar article, each spring is provided in alinement with the key hole of the corresponding cylinder with an opening 31 large enough to permit free passage of the article and avoid deflection of the spring, yet so small that it will not receive the pin 26 of the key, thus insuring release of the dial-wheel by a proper key.

This improved indicator while facilitating the passenger checking work of the conductor, dispenses with and saves the cost of the printed checks in common use which are required in large quantities. It also saves the time of punching and placing them and avoids the liability of loss or misplacement of the checks. The indicator is unlocked and adjusted by practically one and

the same act, being automatically locked by the withdrawal of the key. This renders its use quick and convenient.

In the modification shown in Figures 4 and 5, the locking recesses of the dial-wheel 70 consist of notches 30¹ formed in a rearwardly-extending rim 32 of the dial. The central portion of the dial-wheel has a rearwardly-extending collar 19¹ which surrounds the bearing 17 and is formed with 75 an inwardly-extending flange 20¹ secured to the rear end of the rotary cylinder.

I claim as my invention:—

1. An indicator of the character described, comprising a casing provided in its front 80 wall with a sight-aperture and a bearing extending rearwardly from said wall, a rotary cylinder journaled in said bearing, a dial-wheel including a dial arranged in close proximity to the apertured front wall 85 of the casing, a collar extending rearwardly from the dial and an annular member extending inwardly from said collar and secured to the rear end of said cylinder, and means for locking said cylinder against rotation.

2. An indicator of the character described, comprising a casing provided in its front wall with a sight-aperture and a bearing extending rearwardly from said wall, a rotary 95 cylinder journaled in said bearing, a dial-wheel including a dial arranged in close proximity to the apertured front wall of the casing, a collar extending rearwardly from the dial and an annular member extending 100 inwardly from said collar and secured to the rear end of said cylinder, and means for locking said cylinder against rotation arranged adjacent to the rear end thereof, said cylinder being provided with a longitudinal 105 key hole.

3. An indicator of the character described, comprising a casing provided in its front wall with a sight-aperture and a bearing in said wall, a rotary cylinder journaled 110 in said bearing, a rotary indicating dial arranged in said casing and connected with said cylinder to rotate therewith, said dial having a circular row of locking openings, and a retractible locking device arranged to 115 engage with said openings and having a part located adjacent to the rear end of said cylinder, the latter having a longitudinal opening for the passage of a key.

4. An indicator of the character described, comprising a casing provided in its front 120 wall with a sight-aperture and a bearing in said wall, a rotary cylinder journaled in said bearing, a rotary indicating dial arranged in said casing and connected with said cylinder to rotate therewith, said dial having a circular row of locking openings, and locking means comprising a spring blade 125 extending across the rear end of said cylinder and having a stud arranged to inter- 130

lock with one or another of said openings, said cylinder having a longitudinal opening for the passage of a key to release said locking means and turn the cylinder.

5 5. An indicator of the character described, comprising a casing, having sight-apertures, dial-units arranged in said casing and each including a rotary dial having a circular row of locking openings and a unitary blade 10 spring secured centrally to a support, the arms of the spring extending across the backs of said dials respectively and each arm having a locking stud arranged to engage with one or another of the openings of the 15 companion dial.

6. An indicator of the character described, comprising a casing, a rotary dial, a rotary

cylinder carrying the dial and provided with a key hole, locking means for said dial including a spring blade extending across the 20 inner end of said cylinder and having an opening in line with said key hole, said opening being smaller than the part of the key which engages said spring.

7. An indicator of the character described, 25 comprising a casing, a rotary dial, a rotary cylinder carrying the dial and provided with a key hole and locking means for said dial including a retractible part extending across the rear end of said cylinder, said part having an opening in alinement with said key 30 hole smaller than the member of the key adapted to engage said part to retract it.

CHARLES F. SCHELL.
